UNITED STATES PATENT OFFICE.

ALFRED O. TATE, OF NEW YORK, N. Y.

ELECTROLYTIC CELL.

No. 857,909.

Specification of Letters Patent.

Patented June 25, 1907.

Application filed September 28, 1904. Renewed November 23, 1906. Serial No. 344,787.

To all whom it may concern:

Be it known that I, ALFRED O. TATE, a subject of the King of Great Britain, residing at New York, borough of Manhattan, county 5 and State of New York, have made a new and useful Invention in Electrolytic Cells, of which the following is a specification.

My invention is directed particularly to an improved electrolytic cell designed to decompose the greatest amount of an electrolytic solution with as little expenditure of energy as possible, and it has for its objects, first, the construction of an electrode for such a cell in the most compact form possible with the arrangement of the anodes and cathodes and conducting parts such that a minimum amount of electromotive force may be utilized giving at the same time a maximum amount of current flow through the solution 10 to be acted upon. Second, the arrangement of the anodes and cathodes in such manner that the current flow through them and the solution to be acted upon shall be only between the outer or exposed edges or faces of 15 relatively good conducting laminated strips, plates, or bars, held in close mechanical relation to each other, but sufficiently well insulated between their adjoining faces to prevent the direct passage of the current from 20 one positive strip to its companion negative strip, the lateral or exposed edges or faces constituting a plane surface to which the electrolytic solution to be acted upon is subjected.

35 Prior to my invention electrodes of an electrolytic cell had been connected in multiple relation in such manner that the current flow from the generator through the anodes was directly through the intervening liquid to the 40 cathodes, the action of the current upon the solution being in all instances directly through a well defined volume of liquid, such that the internal resistance of the cell was necessarily so great as to require electrical generators of 45 relatively high voltage, thereby necessitating generators of enormous watt capacity where it was required to electrically treat relatively large volumes of water.

I have discovered that if the anodes and 50 cathodes of an electrolytic cell be composed of laminated strips or plates of good conducting material, connected in multiple relation at their opposite ends with the positive and negative poles of an electric generator and 55 bound together with thin interleaved strips

of insulating material such as to effectually insulate their parallel faces leaving the exterior edges or faces exposed to the solution in parallel planes, electrical generators of very low voltage and large current generating capacity may be utilized and electrolytic action upon solutions in relatively large volumes effected much more economically than is possible with existing types of electrolytic apparatus.

For a full and clear understanding of my invention such as will enable others skilled in the art to construct and use the same reference is had to the accompanying drawings, in which,

Figure 1 is a vertical sectional view taken through a full sized electrode of an electrolytic cell constructed in accordance with my invention, the binding and conducting bolts being shown at the opposite ends of the electrode in elevation. Fig. 2 is a transverse sectional view taken through Fig. 1 on the line x—x and as seen looking thereat from the top toward the bottom of the drawing, the binding bolt being shown in plan view. Fig. 3 is a detail view illustrating the manner of assembling the parts of the electrode.

Referring now to the drawings in detail in all of which like numerals represent like parts wherever used, 1, 1, 2, 2, represent two sets 85 of thin or laminated plates of good conducting material, preferably aluminium, said plates being identically alike in size and structure and interleaved, as shown.

3, 3, 3, represent metallic washers preferably of copper for spacing both sets of plates, and 4, 4, represent good conducting rods, preferably also of copper, and adapted to fit accurately through openings in the pairs of plates 1, 1, 2, 2, with the washers 3, 3, strung 90 thereon between said plates.

5, 5, represent thin strips of good insulating material, such, for instance, as insulating fiber boiled in paraffin and located between the respective pairs of plates 1, 1, 2, 2, the 100 width of said strips being the same as that of the plates.

8, 8, represent end-plates of relatively thick insulating material and of the same width as the plates 1, 1, 2, 2, and 6, 6, are 105 binding plates of metal, such as iron, provided with holes adapted to receive insulating washers 9, 9, 9, through which binding bolts 4, 4, are passed.

7, 7, are nuts, also of copper, and 10, 10 100

are the ends of conductors leading respectively to the positive and negative poles of the source of electrical energy, not shown.

The parts are assembled as follows, having reference particularly to Fig. 3--All of the positive plates, that is to say the plates connected to the positive pole of the generator, are threaded upon the upper bolt 4 with the washers 3 between them, said plates being disposed as condenser plates are, as clearly shown in Fig. 1. The strips of insulating material 5 are located in position between the respective pairs of plates and the insulating end-plates 8, 8, and binding plates 6, 6, are then secured in position with the insulating washers 9 surrounding the ends of the bolts, after which the nuts 7, 7, are firmly secured, binding also the inleading conductors 10, the arrangement being such that when the parts are thus united the electrode plates 1, 1, 2, 2, together with their intermediate insulating strips, are bound into one firm compact electrode with the outer edges or faces of said plates exposed on both sides and located in parallel planes, so that the action of the current as it flows from the + pole of the generator through the cell and the liquid will be through the least possible volume thereof in each instance. In other words, by thus firmly binding the conducting plates together with intervening sheets or strips of insulating material and connecting the opposite ends of the plates in multiple with the + and - poles of a relatively low voltage generator I am enabled to produce upon the lateral edges or faces of the electrode an electrolytic field, so to speak, in which the resistance from the current flow is a minimum, so that as the electrolytic solution is exposed to this field there is upon both faces of the electrode continuous action on the part of the current thus generated at relatively low voltage in all parts of the solution thus exposed. By successively subjecting the solution to this electrolytic field in any preferred manner I am enabled to obtain the best possible electrolytic action with a minimum electromotive force. I prefer to use for the electrode plates 1, 2, thin sheets or strips of aluminium, although other metals may be used, or other good electrical conductors, such as carbon.

In the electrolytic treatment of large volumes of water for industrial uses, as in connection with steam boilers and the like, I prefer to use carbon electrodes constructed in accordance with the structural arrangement disclosed in the accompanying drawings. For the electrolytical treatment of water for house-hold uses, such as drinking purposes and the like I prefer to use aluminium electrodes.

The essence of my invention lies in this closely related disposition of the electrode plates in such manner as to obtain the best

possible electrolytic action with a minimum electromotive force, it being well understood by those skilled in the art that electrolytic action upon a solution is always directly proportional to the quantity of current caused to flow through the solution, and my invention differs essentially from anything heretofore devised, in so far as I am aware, in that instead of causing the current to pass directly through relatively large volumes of water between the faces of the electrodes connected in multiple at their upper ends only, I effect the same result in a very much improved manner by causing the current to flow through closely related sets of relatively large current conducting electrodes and deliver the same to the electrolyte at their lateral edges or faces, the current entering the anodes at one end of the electrode and leaving the cathodes at the other end thereof, thus causing it to act upon the relatively small intermediate volumes of the solution exposed to such edges or faces and over relatively large areas when the anodes and cathodes are arranged and connected up as shown.

Where the electrodes are made of carbon I have obtained most excellent results with a special form, known in the art as Acheson graphitized carbon, manufactured at Niagara Falls, N. Y., and this for the reason that with this form of carbon there is no disintegration of the anode when the cell is in use, a feature which is of material importance, and for this reason especially I prefer to use the type of carbon plates herein referred to.

I do not limit my invention to the specific construction disclosed in the accompanying drawings and hereinbefore described, as the operative elements thereof might be materially departed from, both as to structural arrangement and as to the materials which constitute the effective parts of the electrodes, the essential novelty, as before pointed out, being found generically in an electrode which is made up of sets of closely allied positive and negative plates of relatively large conducting capacity so located or related as to deliver the current to an electrolytic solution through the lateral edges or faces of the same in contradistinction to the delivery thereof through the electrolyte which is located between the parallel faces thereof and in connecting the anode plates in multiple at one end of the electrode and the cathode plates at the other end thereof, as shown.

Having thus described my invention what I claim and desire to secure by Letters Patent of the United States is—

1. An electrode for an electrolytic cell embracing positive and negative conductors of relatively good conductivity located closely adjacent to each other and mechanically and

electrically separated by an insulating medium, the lateral edges or faces only of the conductors being exposed to the electrolytic solution so as to constitute an electrolytic field therein, substantially as described.

5 2. An electrode for an electrolytic cell embracing a series of positive and a series of negative plates of relatively good conductivity, said plates being interleaved and located in close relation to each other; in combination with an insulating medium between each positive and negative plate, the lateral edges or faces only of the plates constituting two electrolytic fields in the electrolytic solution, substantially as described.

10 3. An electrode for an electrolytic cell embracing a series of positive and a series of negative plates of relatively good conductivity, located in close mechanical and electrical relation to each other, the positive and negative elements being separated by an insulating medium, either or both of the lateral edges or faces only of both sets of plates being exposed, substantially as described.

15 4. An electrode for an electrolytic cell embracing a series of positive and a series of negative elements of relatively good conductivity, separated from each other by insulating material and provided with means for binding all of the parts of the electrode together so that only the lateral edges or faces of all of the elements are exposed to the electrolytic solution, substantially as described.

20 5. An electrode for an electrolytic cell embracing a series of positive and a series of negative elements of relatively good conductivity, each series being electrically connected to a conducting bolt or bar of good conductivity and spaced from each other by conducting washers; in combination with insulating strips between the two series of elements; together with binding plates and nuts for the bolts whereby all of the parts are securely bound together in such manner that only the lateral edges or faces of all of the elements are exposed to the electrolytic solution, substantially as described.

25 6. An electrode for an electrolytic cell embracing a series of positive and a series of negative plates of relatively good conductivity, each series being provided with holes or openings at one end and threaded upon a conducting bolt; in combination with spacing conducting washers and insulating strips between the pairs of plates; together with end-plates of insulating medium; binding plates of metal, and nuts for securing all of the parts of the electrode together, the arrangement being such that the lateral edges or faces only of both sets of plates are exposed to the electrolytic solution, substantially as described.

7. An electrode for an electrolytic cell embracing a series of anode and a series of cathode conductors intervening each other, the 65 anode conductors being connected in multiple to the + pole of an electrical generator and the cathode conductors similarly connected at their opposite ends to the negative pole thereof, in combination with insulating 70 material between the anodes and cathodes and means for binding all of said parts together in such manner that the lateral edges or faces only of the anodes and cathodes are exposed to the electrolytic solution substantially as described.

8. An electrode for an electrolytic cell embracing two series of carbon conductors located in close mechanical and electrical relation to each other but separated by insulating media, the lateral edges or faces only of the conductors being exposed, substantially as described.

85 9. An electrode for an electrolytic cell embracing two series of carbon conductors located in close relation to each other and separated by insulating media; in combination with means for binding all of said parts firmly together, the lateral edges or faces only of the conductors constituting the active 90 surfaces of the electrodes, substantially as described.

10. An electrode for an electrolytic cell embracing two series of carbon plates which will not disintegrate under the influence of 95 an electric current in an electrolytic solution, one series being provided with means at their upper ends for connecting them to the positive pole of an electrical generator and the other series being provided with means 100 for connecting them at their lower ends to the negative pole thereof, substantially as described.

11. An electrode for an electrolytic cell embracing two series of carbon plates separated from each other by relatively thin insulating material, one series being provided with means at one end for connecting them in multiple to the positive pole of an electrical generator and the other series being 105 provided with like means at the other end for similarly connecting them to the negative pole thereof, and all of said parts being 110 bound together in such manner that the lateral edges or faces only of the carbon plates 115 are exposed to the electrolytic solution, substantially as described.

In testimony whereof I have signed my name to this specification in the presence of two subscribing witnesses.

ALFRED O. TATE.
